2 SHEETS-SHEET 2.

UNITED STATES PATENT OFFICE.

JAMES P. O'CONNELL, OF CROMPTON, RHODE ISLAND.

SPOOLING-MACHINE.

997,152.

Specification of Letters Patent. Patented July 4, 1911.

Application filed December 12, 1910. Serial No. 596,842.

To all whom it may concern:

Be it known that I, JAMES P. O'CONNELL, a citizen of the United States, residing at Crompton, in the county of Kent and State 5 of Rhode Island, have invented a new and useful Improvement in Spooling-Machines, of which the following is a specification.

This invention pertains to new and useful improvements in spooling machines, and 10 the primary object of the same is to provide new, novel, simple and efficient means to prevent the bobbin over-running itself.

In spooling yarn one of the difficulties which presents itself is the tendency of the 15 bobbin to over-run itself, which results in slack yarn between the bobbin and spool, and owing to the twist that there is in the yarn, kinks are formed, thereby producing a defective yarn on the spool. Further in 20 cases where fine yarn is used the weight of the bobbin where the latter is supported in a groove or trough in ordinary structures commonly employed, the yarn frequently breaks.

25 The present invention is designed to obviate the difficulties which ordinarily present themselves as above noted, and aims to provide a structure which is automatic in operation and creates such tension on the yarn as 30 will prevent the slack yarn with its disadvantages specified above.

In the drawings: Figure 1 is a view in perspective showing the relative position of the invention applied to the frame of a 35 spooling machine, the latter being broken away and in partial section, Fig. 2 is a side elevation of the invention detached from the machine, Fig. 3 is a section on the line 3—3 of Fig. 2, Fig. 4 is a section on the line 4—4 40 of Fig. 2, Fig. 5 is a perspective view of the whirl friction retarding means, and Fig. 6 is a fragmentary perspective view of the friction retarding means for the yarn on the bobbin.

45 In the drawings, 1 designates the upper spindle rail, 2 a carrier for the guide eyes 3 through which latter the yarn passes from the bobbin 4 to the spool 5, the yarn being further engaged by the guide 6 carried by 50 the transverse bar 7. Spool 5 is driven by any approved means, such for instance as the belt 8.

9 designates a holder which is suitably secured to the spindle rail 1 as by jaws 9' 55 and which has journaled therein the spindle 10, provided with the whirl 11. Projecting

outwardly from the holder 9 is an arm 12 of substantial L-form, the upper end of the vertical portion of arm 12 being formed with or having secured thereto a vertical 60 extension or finger 13, which is perforated to receive the shaft or rod 14, the latter being provided with a bent end or projection 15. The vertical portion of arm 12 is formed with a cut-out portion 16, and with 65 a seat 17, the shaft 14 extending across cut-out portion 16 and having a bearing in seat 17.

A brake, preferably formed of wire is constructed to have a shoe 18, formed by looping the wire intermediate its ends, the ends of the looped portion extending outwardly at right angles to shoe 18, to form arms 19 located one above the other, each arm at an intermediate portion being coiled as at 20, 70 to provide sockets or eyes for the reception of the shaft 14, the wire at the ends of the sockets being extended outwardly at right angles to the arms 19 to form second arms 21, which have a bifurcated weight 22, 80 secured thereto in adjustable manner by means of a set screw 23.

The main brake is preferably formed from a sheet metal blank and comprises a shoe 24 which is constructed of a double 85 thickness of the blank formed by doubling or folding the blank as depicted in Fig. 5, the inner ends of the doubled metal being spread outwardly and merge into a socket or eye member 25, which receives shaft 14, 90 so as to have partial rotation thereabout. An arm 26, formed with a slot 27, is carried by the main brake, said arm being formed of an extension of shoe 24, and disposed preferably at right angles thereto. A divided weight 28 is carried by arm 26, the weight divisions extending on opposite sides of arm 26, and being adjustably secured thereto by set screw 29, which penetrates the weight division and extends through 100 slot 27.

By reference to Fig. 2, it will be seen that the shaft 14, has an inclined disposition with respect to the spindle 10 for the purpose of allowing the weights 22 and 28 to 105 respond to the influence of gravity and to consequently cause the brake shoes 18 and 24 to engage the bobbin yarn and spindle whirl respectively.

30 designates an oil duct and reservoir which conveys oil to the spindle bearing, and 31 designates a stop carried by the

holder 9 to engage the top of the whirl 11 to restrict upward movement of the latter.

In operation it will be observed that the shoe 18 due to the presence of the weight 5 22 maintains a uniform friction on the yarn of the full bobbins. The bent end 15 of the shaft 14 is rotatable or adjustable in the extension 13 of the arm 12, and is held in any position to which it may be adjusted by 10 means of a set screw 32. It will thus be obvious that the projection or end 13 of shaft 14 may be adjusted and held against movement in any predetermined position to limit the inward movement of the shoe upon 15 the yarn of the bobbin, so that after a predetermined amount of yarn has been removed from the bobbin, the shoe will not rest on the bobbin, and consequently the yarn will be relieved from that friction exerted 20 by the shoe 18, but as the bobbin would then be free to over-run itself, the second brake which is composed of the weighted pivoted member carrying shoe 24 is resting on the whirl of the spindle and retarding the free 25 running of the latter. Thus at all times regardless of the quantity of the yarn on the bobbin, the latter will be engaged by the brake or retarding means and prevented from over-running itself. Obviously as the 30 bobbin grows smaller its speed becomes greater, and the tension on the yarn is proportionately increased, which makes it possible to dispense with the action of the brake mechanism 18, and to merely employ the 35 brake mechanism 24. Since the weights are adjustable in each instance, it will be apparent that the braking force may be regulated.

Having thus described my invention, I 40 claim as new and desire to secure by Letters Patent;—

1. In a spooling machine, in combination with the bobbin, the spindle thereof, and the spool, a gravity brake for engagement 45 with the bobbin yarn, means to arrest the movement of said brake at a predetermined period, and a gravity actuated brake in engagement with the spindle.

2. In a spooling machine, in combination 50 with the bobbin, the spindle thereof, and the spool, a pair of separate and independent adjustable tension devices, one for engagement with the yarn on the bobbin, and the other for continuous engagement with 55 the spindle, and means for discontinuing the action of one of said devices for a predetermined period.

3. In a spooling machine, in combination with the bobbin, the spindle thereof, and 60 the spool, an arm, a shaft carried by the arm having one end formed to provide a projection, means whereby said shaft may be adjusted, said shaft being inclined with respect to the spindle, a member pivoted 65 on said shaft for engagement with said pro-

jection thereof, said member being formed with a brake shoe at one end to engage the yarn on the bobbin, a weight carried by the opposite end of said member, and a second brake member pivoted to the shaft formed 70 with a shoe to engage the spindle at one end and carrying a weight at its opposite end.

4. In a spooling machine, in combination with the bobbin, the spindle thereof, and the spool, an adjustable shaft carrying a 75 projection at one end, a brake mechanism movably mounted on the shaft and having a portion to engage said projection to limit the inward movement of the brake with respect to the bobbin, and a second brake 80 mechanism movably mounted on the shaft to engage with the bobbin spindle.

5. In a spooling machine, in combination with the bobbin, the spindle thereof, and the spool, an adjustable shaft carrying a 85 projection at one end, a brake mechanism movable on said shaft and composed of two parts arranged at right angles to each other, one of said parts being formed to provide a brake shoe, a weight adjustably carried 90 by the other part, said last named part being adapted to engage said projection whereby to limit the movement of the shoe with respect to the bobbin, a second brake mechanism movable on the shaft and composed 95 of two members arranged at right angles to each other, one of said members forming a brake shoe to engage with the spindle, and the other member having an adjustable weight carried thereby.

6. In a spooling machine, in combination with the bobbin, the spindle thereof, and the spool, an adjustable shaft carrying a projection at one end, and a pair of independent speed retarding devices mounted on said 105 shaft, one of said devices being for continuous engagement with the yarn on the spindle, the other of said devices being for engagement with the bobbin and for engagement with said projection to limit the extent of movement of said device with respect to the bobbin.

7. In a spooling machine, in combination with the bobbin, the spindle thereof, and the spool, a shaft, a brake mounted on the 115 shaft and formed of a section of sheet metal having two parts arranged at right angles to each other, one of said parts being folded or doubled to provide a brake shoe of twice the thickness of the metal, an intermediate 120 part of said metal being bent to form a socket to receive the shaft, and a weight adjustably mounted on the other of said right angular parts.

8. In a spooling machine, in combination 125 with the bobbin, the spindle thereof, and the spool, a shaft, a brake mounted on the shaft and composed of a piece of wire looped to form a brake shoe, the ends of the loops being extended at right angles thereto and 130

coiled to form eyes to receive the shaft, the ends of the eyes being extended to form arms which are disposed at right angles to the loop extensor, and a divided weight receiving said arms therebetween and adjustably clamped thereto.

In testimony whereof I have signed my

name to this specification in the presence of two subscribing witnesses.

JAMES P. O'CONNELL.
